HANDBAG LOCK

David Damast, 22-14 40th Ave.,
Long Island City, N.Y. 11101

Filed Jan. 16, 1967, Ser. No. 5,424

Term of patent 3½ years

(Cl. D87—2)

FIG. 1 is a front elevational view of a handbag lock showing my new design in closed position,

FIG. 2 is an exploded perspective view showing the turn lock member in open position,

FIG. 3 is a top end view thereof, and

FIG. 4 is a side elevational view thereof.

The rear elevational view is the same as the front without the surface ornamentation and turn lock.

I claim:

The ornamental design for a handbag lock, substantially as shown and described.
